INTERNAL-COMBUSTION ENGINE.

1,164,550.

Specification of Letters Patent.

Patented Dec. 14, 1915.

Application filed September 27, 1911. Serial No. 651,509.

To all whom it may concern:

Be it known that I, ADOLPH ROSNER, a subject of the Emperor of Austria-Hungary, and a resident of Bridgeport, in the county 5 of Fairfield and State of Connecticut, have invented an Improvement in Internal-Combustion Engines, of which the following description, in connection with the accompanying drawings, is a specification, like characters on the drawings representing like parts.

This invention relates to internal combustion engines, and particularly to the means for controlling the admission of fuel to the 15 cylinder and the exhaust of the waste gases therefrom.

The invention will be best understood by reference to the following description when taken in connection with the accompanying 20 illustration of one specific embodiment thereof, while its scope will be more particularly pointed out in the appended claims.

In the drawing: the figure is a sectional 25 elevation taken through a cylinder of an engine embodying one form of the invention.

Referring to the embodiment of the invention shown in the drawing, the engine 30 there illustrated is provided with a main outer shell 1 which has the water jacket 2, and is supported upon the crank casing 3. A working piston 4 is connected by the rod 5 to the crank 6 and crank shaft 7. The 35 rear end of the cylinder space is closed by the cylinder head 8, which has the water jacket 9 communicating with the cylinder jacket 2 and having also the centrally arranged spark plug 10.

40 The cylinder 1 is provided at one side with the admission port 11 opening from the admission chamber 12, such port extending part way around said cylinder, the latter being provided on the opposite side with 45 an exhaust port 13 opening from the exhaust chamber 14.

In the described embodiment of the invention the piston 4 works in direct sliding contact with the walls of an inner sleeve 50 or lining cylinder 15, which sleeve is bolted to the crank casing 3 and has its upper or rear edges terminating at the lower edges of the ports 11 and 13. The latter are also preferably located beyond the rearward limit of piston travel, which is represented by dotted lines in the drawing so that the

ports open directly into the explosion chamber, giving a very free admission and exhaust except when covered by the valves about to be described.

To control communication between the ports 11 and 13 and the explosion chamber, there is provided slide valve means working in an annular space between the inner and outer cylinders. Such valve means herein comprises two separate slide valves 16 and 17, each in the form of an arc-shaped segment, filling the annular space between the two cylinders. The former serves to control the inlet port 11, and the latter the exhaust port 13. While slides of different extent or proportions might be employed, herein each one is semi-cylindrical, the edges of one being in sliding contact with the edges of the other.

The slide valves are so located that they may be projected beyond the edges of the inner cylinder 15, to cover the ports 11 and 13, as required. This permits the slide to be constructed without forming ports therein, the projecting ends of the sleeves being the only portions exposed to the pressure of the combustion chamber and the heat thereof, the major portion of each slide being protected from heat and pressure in the annular space provided. The pressure in the explosion chamber during the compression and working strokes forces the separate and independent segments outwardly against their seats, so as to provide for the adequate seating of the valves and prevent all leakage of pressure about the ends of the same. The slide valves being located in front of the explosion space of the engine, they are not required to engage or coöperate with the cylinder head in their movements, and the head may be given a plain formation, serving merely as an end closure for the cylinder and providing the most efficient form of combustion chamber with any desired clearance. The slide valves may be actuated by any suitable means in timed relation to the movements of the piston, and with reference to the admission, compression, firing and exhaust. Each slide valve 90 is actuated by mechanism substantially the same, and differing only in adjustment, and one only need be described. Referring to the actuating mechanism for the valve 16, the latter is provided below the walls of the cylinder 1 with a lug 18, which is connected by the link 19 to one end of the lever 20.

The lever is pivoted at 21 and carries the cam roller 22, which latter is normally pressed down by the spring 23 and push rod 24. The roller rests against the upper 5 adjustable end of a lifting rod 25, the lower end of which carries a cam roll 26 bearing against the cam 27 on the cam shaft 28. The cam shaft 28 for the valve 16 and the shaft 29 for the valve 17 are driven by 10 suitable gearing from the crank shaft at one-half speed of the latter.

The cams are so adjusted that on the commencement of the admission stroke the exhaust valve has been lifted by its cam to 15 project the end of the valve over and to cover the exhaust port, the admission port at that time being opened through the retraction or depression of the admission valve within the annular space between the 20 cylinders. At the end of the admission stroke the admission valve is lifted, leaving both ports closed, and the next rearward or compression stroke takes place. On the next forward or firing stroke the exhaust 25 valve is opened near the end of the stroke, and maintained open during the next rearward piston stroke, which completes the cycle.

It will be seen that the valves require but 30 a slight movement to cover the ports, and this movement being effected by cams it can be made to take place almost instantly, giving the benefit of the full port opening at the outset.

While I have herein shown and described 35 for purposes of illustration one specific form of the invention, it is to be understood that the latter is not limited to the precise construction of features disclosed nor to the 40 form or relative arrangements of parts nor to the particular type of engine described, but that extensive modifications may be made in the illustrated embodiment of the invention without departing from the spirit 45 thereof.

Claims:

1. An internal combustion engine having 50 an outer cylinder, an inner cylinder separated therefrom by an annular space, a piston working in said inner cylinder, ports in said outer cylinder beyond said inner cylinder and beyond said annular space, slide valves in said space, and means for moving said valves to project their ends over said 55 ports to close the same or withdraw the same to open the ports.

2. An internal combustion engine comprising a fixed outer cylinder, a fixed inner cylinder in said outer cylinder, a piston, a 60 port, and means between said inner and outer cylinder for controlling said port comprising a movable slide valve plate, said plate, when opening said port, having its

end adapted to be alternately projected over and withdrawn from the port. 65

3. An internal combustion engine comprising a fixed cylinder with a cylinder head, said cylinder having admission and exhaust ports, a piston, means for controlling said ports comprising a pair of independently movable, arc-shaped slide valve plates, said plates being adapted to be moved each to cover its respective port with its end exposed to the pressure of the explosion chamber or to be moved to open its port, 70 said plates being adapted to have their ends alternately projected over and withdrawn from said ports, and a fixed inner cylinder between said valve plates and said piston. 75

4. An internal combustion engine comprising a fixed outer cylinder having admission and exhaust ports, said ports being directly opposite each other, a fixed inner cylinder separated therefrom by an annular space, a piston within said inner cylinder, 85 and segmental valves working in said annular space and adapted to have their ends alternately withdrawn therein or projected therefrom respectively to open and close the ports. 90

5. An internal combustion engine comprising a fixed cylinder with a cylinder head, said cylinder having admission and exhaust ports directly opposite each other, a piston, means for controlling said ports comprising a pair of independently movable arc-shaped slide valve plates, said plates being adapted to be moved each to cover its respective port with its end exposed to the pressure of the explosion chamber or to be moved to open its port, said plates being adapted to have their ends alternately projected over and withdrawn from said ports and a fixed inner cylinder between said valve plates and said piston. 95 100

6. An internal combustion engine comprising a fixed outer cylinder having admission and exhaust ports, a fixed inner cylinder separated therefrom by an annular space, a piston within said inner cylinder and segmental valves working in said annular space and having ends adapted to be alternately withdrawn within the space or projected therefrom respectively to open and close the ports, said projected ends being wholly exposed to the pressure of the cylinder space, and having sliding contact with the cylinder walls only on their exterior faces. 110 115

In testimony whereof, I have signed my name to this specification, in the presence of two subscribing witnesses.

ADOLPH ROSNER.
